(57) CLAIM

The ornamental design for a combined collar and stole with display lanyard, as shown and described.

DESCRIPTION

FIG. 1 is a front view of the new design for a combined collar and stole with display lanyard;
FIG. 2 is a back view, thereof;
FIG. 3 is a top view, thereof;
FIG. 4 is a bottom view, thereof;
FIG. 5 is a left side view, the right side view being a mirror image, thereof;
FIG. 6 is a front perspective view of the claimed design in a worn configuration;
FIG. 7 is a back view thereof;
FIG. 8 is a front and side thereof with environment displayed on the claimed design;
FIG. 9 is a back and side view thereof; and,
FIG. 10 is a front view of the claimed design laid flat.
The broken line outline of the partial human figure in FIGS. 6-9 assists in illustrating how the combined collar and stole with display lanyard may appear when in a position of use but forms no part of the claimed design. The broken and dotted lines within the bounds of the claimed design in FIG. 8 assist in illustrating how the invention may appear when used to display pins and memorabilia and a name badge represented by the broken and dotted line illustrations which depict environment associated with the claim but form no part of the claimed design. The broken and dotted lines within the bounds of the claimed design in FIG. 9 assist in showing how the invention may appear when used to display printed logos and sponsor branding in this configuration depicting environment associated with the claim but form no part of the claimed design. The evenly spaced broken lines in FIG. 4 depict stitching which forms no part of the claimed design. The broken lines depicting a hanger within FIG. 10 assist in illustrating how the invention may appear in an alternate position of use, but form no part of the claimed design.
